UNITED STATES PATENT OFFICE.

CARL E. TURNQUIST, OF SAN GABRIEL, CALIFORNIA, ASSIGNOR OF ONE-HALF TO
ULYSSES GRANT ORENDOFF, OF CANTON, ILLINOIS.

COMBINED CALENDAR CALCULATOR AND CHART.

Application filed February 6, 1924. Serial No. 691,005.

This invention relates to a combined calendar calculator and chart and is more particularly adapted for use in connection with an incubator for hatching eggs.

5 The primary object of the present invention is to improve the construction of the calendar calculator and chart shown, described and claimed in my application Serial No. 612,211 filed January 12, 1923.

10 A further object of the invention is to improve and simplify the calendar calculator generally.

15 A still further object of the invention is to provide a novel construction of a calendar calculator by means of which the rotatable discs are frictionally secured against rotation.

20 These and other objects are accomplished by providing a construction and an arrangement of the various parts in the manner hereinafter described and particularly pointed out in the appended claims.

25 Referring to the drawings, Fig. 1 is a top plan view showing the preferred embodiment of my improved calendar calculator.

Fig. 2 is a cross sectional view taken on the vertical plane passing through the longitudinal axis of the calendar calculator in Fig. 1.

30 Fig. 3 is a top plan view showing the construction of one of the rotatable discs, and

Fig. 4 is a top plan view of one of the strips which are positioned between the rotatable discs for frictionally securing them against rotation.

In carrying out my invention I have provided a novel form of master or stationary disc 10, which has formed integrally therewith an upwardly extending portion 11, which forms a support or handle. In order to reinforce and strengthen this handle portion I have provided an extension thereof which is formed integrally with the portion 11, and folded back as shown at 12 to form a reinforcing member 13 secured to rear side of the calendar calculator. Between the master disc 10 and the reinforced portion 13 is rotatably mounted a plurality of discs hereinafter described. The master disc 10 has printed on a sector 14 thereof the twelve calendar months of the year arranged in the arc of a circle as shown at 15. Arranged consecutively around the remaining arc of the circle are the numerals 1 to 21 inclusive, which denote the length of time

normally required for hatching a setting of eggs. The master disc is provided with a radial line 16 with the words "Date set" indicating the day on which the eggs were placed in the incubator. The radial line 17 on the master disc points to the indication of the expiration of the twenty-one days or the time necessary for normally hatching a setting of eggs. Pivoted concentrically with the master disc is an indicator 18 which is adapted to be adjusted to indicate the calendar month in which the incubator is set.

Another important feature of my improved calendar calculator is the provision of means for reinforcing and frictionally securing the rotatable calendar discs in their positions to which they are adjusted. This mechanism comprises a plurality of strips 19 which are positioned between the rotatable discs 20, 21, 22 and 23. The discs 20, 21, 22 and 23 are pivoted concentrically to the master disc 10 by an eyelet rivet 24. Each of the strips 19 as well as a supplemental strip 25 is secured in place between the rotatable discs by the eyelet rivet 24 as clearly shown in Figs. 1 and 2. The upper ends of the strips 19 are secured to the handle portions 11 and 13 of the master disc 10 by a second eyelet rivet 26. It will of course be understood that these strips are preferably made of paper but might well be made of brass, aluminum or celluloid. It will also be seen from the above description that each of the discs 20, 21, 22 and 23 are separated from each other by the strips 19 in such a manner that the strips offer a frictional resistance to the rotation of each of the discs and thereby frictionally lock each of these discs in the position to which they are adjusted so that each disc may be individually adjusted without affecting the adjustment of any of the other discs. The supplemental strip 25 is secured in position by the eyelet rivets 24 and 26 and extends upwardly between the handle portions 11 and 13 of the master disc 10 to the top portion thereof and secured in position by an additional eyelet rivet 27, and thereby further reinforcing the handle portion of the calendar calculator.

Another important feature of my improved calendar calculator is the provision of a novel construction of a rotatable disc which permits the easy adjustment of these discs about their common pivots. This con-

struction comprises the bevelling or tapering of the discs as shown at 28 of that portion of the disc which extends outwardly on the periphery thereof, as shown at 29, and 5 carries the calendar days of the month. This bevelled or tapered portion 28 of each of the rotatable discs 20, 21, 22 and 23 is arranged so that when the discs are rotated between the frictional strips 19 they will 10 be easily guided through without tearing or straining the discs unnecessarily and thereby prolong the life of the calendar calculator. The disc 20 carries on its outwardly projecting peripheral portion thereof the 15 calendar days from 1 to 7 inclusive and the disc 21 carries the calendar days from 8 to 14 inclusive. The disc 22 carries the calendar days from 15 to 21 inclusive and the disc 23 carries the calendar days from 22 to 20 21 inclusive. On the front face of the calendar calculator and preferably on the upper portion of the handle 11 I have provided a record pad 30 which is for the purpose of keeping a permanent record of the 25 results of each setting.

In the operation of my improved combined calendar calculator and chart let us assume that the setting of eggs is placed in the incubator on the fourth day of July, 30 as indicated in Fig. 1, the pointer or indicator 18 pointing to July and the rotatable disc 20 is rotated until the numeral 4 registers with the line 16 which is the "date set". Then each of the discs 21, 22 and 23 35 is adjusted so that the calendar days are arranged in consecutive order and when in this position the numeral 21 on the radial line 17 will register with 25 on the disc 23 indicating that the setting of eggs will be 40 hatched on the 25th day of July. The master disc of course is provided with instructions between the first and the twenty-first, indicating the various operations necessary to obtain the best results from a setting of 45 eggs. In the adjustment of the discs 20, 21, 22 and 23 it will readily be seen that the strips 19 not only separate these discs but frictionally secure them against rotation so 50 that each of the discs may be adjusted independently of the other, and it will, of course, be seen that by tapering or inclining that portion of each of the discs that carry the calendar dates the discs may readily be rotated between the strips with great 55 facility.

While in the above specification I have described one embodiment which my invention may assume in practice, it will of course be understood that the same is capable of 60 modification and that modification may be made without departing from the spirit and scope of the invention as expressed in the following claims.

What I claim as my invention and desire 65 to secure by Letters Patent is:

1. A combined calendar and chart comprising a stationary master disc, a handle portion formed integrally with said master disc, and a plurality of rotatably related calendar discs operatively related to said master disc, the master disc having a period of time indicated thereon, the period of time being subdivided into days and progressively indicated, the days indicated on the calendar discs being adapted to be brought 70 into registration with the days indicated on the master disc.

2. A combined calendar and chart comprising a stationary master disc, a handle formed integrally with said master disc 80 having a portion thereof folded rearwardly to form a reinforcing member for the handle and master disc, and a plurality of rotatably related calendar discs operatively related to said master discs and positioned 85 between said master disc and said reinforcing member.

3. A combined calendar and chart comprising a stationary master disc, a handle formed integrally with said master disc, a 90 plurality of rotatably related calendar discs operatively related to said master disc, and means connected with said handle and said master disc for frictionally securing said 95 rotatable discs against rotation.

4. A combined calendar and chart comprising a stationary master disc, a handle formed integrally with said master disc, a plurality of rotatably related calendar discs operatively related to said master disc, and means connected with said handle and said master disc for impinging on and securing 100 said rotatable discs against rotation.

5. A combined calendar and chart comprising a stationary master disc having a 105 handle, a plurality of rotatably related calendar discs operatively related to said master disc, and means secured to said handle and positioned between and extending radially across the face of said rotatable discs for 110 frictionally resisting the rotation of said last named discs.

6. A combined calendar and chart comprising a stationary master disc having a handle, a plurality of rotatably related calendar discs operatively related to said master disc, and means secured to said master disc and said handle for frictionally resisting 115 rotation of said rotatable discs.

7. A combined calendar and chart comprising a stationary master disc having a handle, a plurality of rotatably related calendar discs operatively related to said master disc, and a strip positioned between said rotatable discs and secured to said handle for 125 resisting rotation of said discs.

8. A combined calendar and chart comprising a stationary master disc having a handle, a plurality of rotatably related calendar discs operatively related to said mas- 130

ter disc, and a plurality of strips secured to said master disc and said handle for securing said rotatable discs against rotation.

9. A combined calendar and chart comprising a stationary master disc having a handle, a plurality of rotatably related calendar discs operatively related to the master disc, a plurality of strips positioned between said rotatable disc, each of said discs being provided with a peripherally projecting portion having a period of time indicated thereon, and means whereby the projecting portions of said rotatable discs may be rotated between said strips unobstructedly.
10. A combined calendar and chart comprising a stationary master disc having a handle, a plurality of rotatably related calendar discs operatively related to the master disc, a plurality of strips positioned between said rotatable disc, each of said discs being provided with a peripherally projecting portion having a period of time indicated thereon, and bevelled edges formed on said projecting portions of said rotatable discs whereby said last named discs may be rotated between said strips unobstructedly.
11. A combined calendar and chart, com-

prising a stationary member including a master disc, a plurality of rotatably related calendar discs operatively related to said master disc, and a plurality of strips positioned between said discs and rigidly connected at their opposite ends to said stationary member for resisting relative rotation of said discs.

12. A combined calendar and chart, comprising a stationary member including a master disc, a plurality of rotatably related calendar discs operatively related to said master disc, and means positioned between said discs and rigidly connected to said stationary member for resisting relative rotation of said discs.

13. A combined calendar and chart comprising a stationary member including a master disc, a plurality of rotatably related calendar discs operatively related to said master disc, and means rigidly connected to said stationary member for resisting rotation of said calendar discs.

In testimony whereof I have signed my name to this specification on this 30th day of January, A. D. 1924.

CARL E. TURNQUIST.
